UNITED STATES PATENT OFFICE.

COLIN A. HAWES, OF PAWTUCKET, RHODE ISLAND, ASSIGNOR TO EASTON AND BURNHAM MACHINE COMPANY.

BOBBIN-CLUTCHING DEVICE FOR SPINDLES.

No. 851,884.

Specification of Letters Patent.

Patented April 30, 1907.

Application filed July 7, 1905. Serial No. 268,720.

To all whom it may concern:

Be it known that I, COLIN A. HAWES, a citizen of the United States, residing at Pawtucket, in the State of Rhode Island, have 5 invented a new and useful Improvement in Bobbin-Clutching Devices for Spindles, of which the following is a specification.

This invention has for its object the production of novel and efficient means for 10 holding the bobbin in operative position upon the spindle during its revolution, and it relates to that class of bobbin clutching devices, which are adapted to engage with the bobbin externally of its head, through 15 the medium of centrifugal force.

In centrifugally operated bobbin clutching devices heretofore constructed for action exteriorly of the head of the bobbin, the clutching levers have been rendered operative by 20 reason of the preponderance in weight of the outwardly moving arms of the said clutching levers, over that of the inwardly moving arms which engage with the head of the bobbin, and hence such clutching levers have 25 been designated as centrifugally acting. I have, however, obtained important advantages by so constructing the clutching levers that their inwardly moving engaging arms are of greater weight than that of the outwardly moving arms, so that the centrifugal force exerted upon the inwardly moving engaging arms will be greater than that exerted upon those arms by means of which the said engaging arms are actuated to engagement. 35

In the accompanying drawings:—Figure 1 represents a side elevation of one form of my improved bobbin clutching device, showing also a portion of the spindle, and of the 40 bobbin. Fig. 2 represents an axial section of the bobbin clutching device and of the bobbin shown in Fig. 1. Fig. 3 represents a top view with the bobbin removed. Fig. 4 represents a top view of the collar which provides a fulcrum for the centrifugal bobbin clutching levers. Fig. 5 represents an outer side view of one of the bobbin clutching levers. Fig. 6 represents an inner side view of the same. Fig. 7 represents a top view of the same. Fig. 8 represents an axial section as in Fig. 2, showing the insertion of a washer under the head of the bobbin. Fig. 9 represents the top view of a collar provided with

projections which serve as a support for the bobbin, instead of allowing the bobbin to 55 rest upon the offset portion of the bobbin supporting levers. Fig. 10 represents a section as in Fig. 2, showing a modified construction of the collar with the bobbin resting thereon. Fig. 11 represents the same 60 with the inserted washer. Fig. 12 represents a broken side elevation showing a modification. Fig. 13 represents an axial section of the device shown in Fig. 12. Fig. 14 represents a top view of the fulcrum collar 65 shown in Fig. 12. Fig. 15 represents a side view of one of the bobbin clutching levers shown in Fig. 12. Fig. 16 represents a top view of the same. Fig. 17 represents a broken side elevation in which the centrifugal 70 bobbin clutching levers are inclosed in a protecting shield.

In the drawings, A represents the spindle, B the whirl attached to the spindle, and C the bobbin. The whirl B is provided with 75 the upwardly extending tapering sleeve D, upon which is placed the tightly fitting but readily removable annular collar E, the said collar being provided with the notches a a a, which are adapted to receive the axially arranged bobbin clutching levers F F F, the said levers resting at their lower ends upon the upper surface b of the whirl, and having the under side of their outwardly offset upper portion c, raised above the upper surface of the 85 collar E, whereby the said levers will be supported by their lower ends resting upon the upper surface of the whirl B, and not by their engagement with the upper surface of the said collar E. The horizontally offset portion c, is provided with the upwardly extending flange d, which is preferably made in curved form, to engage with the periphery of the head e of the bobbin C, which rests upon the upper horizontal surface of 90 the offset portion c of the bobbin holding levers and is therefore supported in vertical position independently of the said collar. The weight of the arm f of the bobbin clutching lever F, which is below its fulcrum point l of the collar E, is preferably made much less than that of the shorter engaging arm g, which is above the said collar, which is contrary to the construction heretofore employed in bobbin clutching levers, said levers 95 having been made dependent for their effi- 100 105

ciency upon the greater mass of metal employed in their lower actuating arms. In my invention I employ centrifugal leverage and not direct centrifugal action, to clutch the head of the bobbin. I am therefore enabled to make the clutching levers much lighter and have been able to carry the lower arms of the said clutching levers much closer to the axis of the spindle than heretofore.

10. In Fig. 8, a loose washer *h* is placed between the offset portion *c* of the clutching levers *F* and the head of the bobbin, in order to protect the head of the bobbin from wear, and to form a stop for the inward movement 15 of the engaging arms *g* of the said clutching levers.

In Figs. 9 and 10, the collar *E* is shown as provided with the upwardly extending lugs *k* *k*, which serve to raise the washer *h* to such 20 a height as to free the bobbin clutching levers *F* from the weight of the bobbin, the weight of the bobbin in this case being supported entirely by the collar *E*. The clutching levers *F* are provided with the lateral extensions *j* *j*, which serve to prevent the said 25 levers from rising in the holding notches *a* of the collar.

A modification is shown in Figs. 12 and 13, in which a fulcrum collar *E'* is employed provided with the upturned flange *m*, and with 30 the perforations *i*, *i*, *i*, adapted to receive the engaging arms *g* of the bobbin clutching levers *F*, the said levers being constructed of sheet metal as shown in Figs. 15 and 16. 35 And above the collar *E'* upon the sleeve *D* of the whirl, is placed the washer *h* which serves to support the bobbin and also to limit the inward movement of the engaging arms *g* of the levers whenever the bobbin is lifted from the 40 rapidly revolving spindle, and as before described the clutching action is dependent upon the leverage of the lighter lower arms *f* and not upon the direct centrifugal action of a preponderant weight.

45. In connection with the bobbin clutching levers *F*, shown in Figs. 12 and 13, I have preferred to employ a continuous shield *G*, for protecting the lower arms of the said levers, as shown in Fig. 17.

50. I claim as my invention:—

1. The combination of a spinning spindle, and a bobbin held upon the spindle, with bobbin clutching levers having lower arms longer than their upper arms, and a fulcrum 55 relatively nearer their upper ends, said upper arms serving to support the bobbin by engaging with the exterior of its head, the weight of the upper engaging arms being greater than that of the said lower arms, and 60 the center of gravity of the lower arms being farther from the fulcrum than that of the upper arms.

2. The combination of a spinning spindle, with centrifugal clutching levers having the 65 bobbin-clutching arms of the said levers

heavier than those by means of which the said clutching arms are actuated to clutch the exterior of the head of the bobbin.

3. The combination of a spinning spindle, the whirl and sleeve secured thereto, a collar 70 mounted on the sleeve, and centrifugal clutching levers fulcrumed on the said collar and adapted to exteriorly engage and rotate a bobbin, and having the bobbin clutching arms of greater weight than that of the arms 75 by means of which they are actuated.

4. The combination of a spinning spindle, with a plurality of centrifugal bobbin-clutching levers mounted to rotate therewith, and symmetrically arranged with reference to 80 their axis of rotation, said levers having their bobbin-clutching arms made heavier than the arms by which they are actuated to engage exteriorly with the head of the bobbin.

5. The combination of a spinning spindle, 85 a sleeve secured thereto, and the whirl, with a plurality of centrifugal bobbin clutching levers symmetrically arranged with relation to the axis of the spindle, and having their upper arms made heavier and shorter than 90 their downwardly extending lower arms, and mounted to rest on the whirl, the heavier upper arms being moved inwardly to externally engage the head of the bobbin by reason of the greater distance of the center of gravity 95 of the lower arms from the fulcrum than that of the upper arms.

6. The combination of a spinning spindle, and a fulcrum with centrifugal bobbin clutching levers having their upper arms made 100 heavier and shorter than their downwardly extending lower arms, whereby their heavier upper arms will be moved toward the axis of the spindle, when under rotation by the advantageous centrifugal action of the downwardly extending lighter arms.

7. A spinning spindle having an attached whirl and sleeve, a series of bobbin clutching levers mounted to rotate with said whirl and sleeve, and to exteriorly engage the head of 110 a bobbin, and having the weight of their upper engaging arms made greater than the weight of their downwardly extending longer lower arms, and having the outward movement of their upper arms limited by the engagement of their lower arms with the side 115 of the said sleeve.

8. A spinning spindle, a collar rotating therewith, a plurality of centrifugal bobbin-clutching levers fulcrumed thereon, and having their upper arms laterally curved to externally engage and hold the head of a bobbin each of the said levers being made heavier above its fulcrum than below the same.

9. A spinning spindle, a collar rotatable 125 therewith, a plurality of centrifugal bobbin-clutching levers fulcrumed thereon, and having the engaging arms above their fulcrums heavier than the arms below the same, and a protecting shield surrounding the said levers. 130

10. The combination of a spinning spindle, the whirl and sleeve with the collar, and the centrifugal bobbin-clutching levers fulcrumed on the said collar, and supported at their lower ends by the whirl and adapted at their upper ends to externally engage the head of a bobbin.
11. The combination of a spinning spindle, the whirl and the sleeve, with the collar provided with the notches, and adapted to embrace the sleeve, and the centrifugal bobbin-clutching levers held in the said notches of the collar the engaging upper ends of the said clutching levers being heavier than their lower ends.
12. The combination of a spinning spindle, the whirl, the sleeve and the collar with the bobbin clutching levers fulcrumed at the outer side of the openings of the collar and provided with means for preventing upward movement therein the engaging upper ends of the said clutching levers being heavier than their lower ends.
13. The combination of a spinning spindle, the whirl, the sleeve, and the collar, with the centrifugal bobbin-clutching levers, fulcrumed at the outer side of the openings of the collar, and provided with lateral extensions for preventing the upward movement of the levers the engaging upper ends of the said clutching levers being heavier than their lower ends.
14. The combination of a spinning spindle, the whirl, and the sleeve, with the collar held upon the sleeve, the horizontally offset cen-
- trifugal bobbin-clutching levers, and the washer for supporting the bobbin.
15. The combination of a spinning spindle, the whirl, and the sleeve, with the collar held upon the sleeve, the horizontally offset centrifugal bobbin-clutching levers, and the bobbin supporting washer, resting upon the offset portion of the said levers.
16. The combination of a spinning spindle, the whirl, the sleeve, the perforated fulcrum collar held upon the sleeve, the centrifugal bobbin-clutching levers fulcrumed in the perforations of the fulcrum collar for engagement with the exterior of the head of the bobbin, and having their engaging upper ends heavier than their lower ends, and means for limiting the inward movement of the engaging ends of the said levers upon the removal of the bobbin from the revolving spindle.
17. The combination of a spinning spindle, the whirl, the sleeve, the perforated fulcrum collar held upon the sleeve, the centrifugal bobbin-clutching levers fulcrumed in the perforations of the fulcrum collar for engagement with the exterior of the head of the bobbin, and having their engaging upper ends heavier than their lower ends, and the washer arranged above the fulcrum collar for limiting the inward movement of the engaging ends of the said levers upon the removal of the bobbin from the revolving spindle.
